DESIGN FOR A TOOTHERBRUSH

Robert W. Stavely, Detroit, Mich.

Application November 17, 1945, Serial No. 123,851

Term of patent 14 years

(Cl. D9—2)

To all whom it may concern:

Be it known that I, Robert W. Stavely, a citizen of the United States, residing at Detroit, in the county of Wayne and State of Michigan, have invented a new, original, and ornamental Design for a Toothbrush, of which the following is a specification, reference being had to the accompanying drawing, forming a part thereof, and wherein Fig. 1 is a side elevational view of a toothbrush showing my new design and Fig. 2 a rear elevational view. The essential features of the design are shown in full lines in the drawing.

I claim:

The ornamental design for a toothbrush, as shown and described.

ROBERT W. STAVELY.
